SAUSAGE SMOKING DEVICE

William Bogner, Elmhurst, N. Y.

Application March 4, 1941, Serial No. 381,625

3 Claims. (Cl. 17—44.4)

This invention relates to new and useful improvements in racks for supporting frankfurters, bolognas and similar products during the smoking process thereof.

It is one object of the present invention to provide a new and improved bar for supporting sausages and similar articles during the process of smoking them.

A feature of the invention resides in a novel construction whereby the point of contact between the bar and the product may be varied from time to time during the smoking process.

This feature of the invention is important since it results in even and uniform coloration of the finished product.

Another feature of the invention resides in a novel construction whereby the supporting bar will not interfere with the passage of smoke to all portions of the product being processed.

In the accompanying drawing, which illustrates one form of the invention,

Figure 1 is a fragmentary view in side elevation illustrating a portion of a smoking tree or rack with a supporting bar in position thereon,

Figure 2 is a fragmentary top plan view,

Figure 3 is a detail sectional view on an enlarged scale taken substantially on the line 3—3 of Figure 1,

Figure 4 is a detail sectional view on an enlarged scale taken substantially on the line 4—4 of Figure 2, and

Figure 5 is a perspective view of the supporting bar, the bar being partly broken away.

The supporting bars are designated A and in use, a plurality of such bars are supported in a rack or tree which is designated B.

The rack or tree B is formed of metal, preferably in the form of a rectangular structure constructed of angle irons. It consists of vertical corner members 10, side bars 11, and end bars 12, the side and end bars being horizontally disposed and connected to the corner members and being suitably secured thereto to form a rack-like structure.

The supporting bars A rest upon the side members 11 as best illustrated in Figures 1 and 2. Any suitable means is provided upon one of these side members to prevent lateral movement of one end of the supporting bars. In the accompanying drawing, this means consists of an upstanding flange or the like 13 which is notched as at 14 to receive certain elements of the supporting bars in a manner to be hereinafter more specifically described.

One of the supporting bars is shown in detail

in Figure 5 and I will describe the construction of these bars by reference to said figure.

Referring to said Figure 5, each of the bars consists of two side members 16 preferably of arcuate cross-sectional form. These side members 16 are held in rigid spaced relation to each other by means of spacing elements 17 secured in position between the bars by pins, rivets or the like 18. The spacing elements 17 are also spaced with respect to each other and the pins or rivets 18 pass through them as best illustrated in Figure 4.

Mounted between the side members 16, there is a bar 20 and said bar, near each of its ends, has an angularly disposed lug or extension 21 which is provided with an elongated slot 22. These slots 22 receive the pins or rivets 18 at their respective ends of the bar.

The normal position of the bar 20 is one between the side members 16 with its top edge in substantially the same plane as the top edges of the side members 16. By reason of the angularly disposed slots 22, it will be obvious that if the bars 20 are reciprocated upon the pins 18 or rivets 18 from their lowest position, they will be moved to an elevated position with respect to the side members 16 in which position a bar 20 is shown in Figure 4 of the drawing.

Means is provided for reciprocating the bars 20 of the supporting bars A and this means is so constructed as to operate simultaneously, the bars 20 of a series of supporting bars A.

Extending along the side members 11 of the rack or tree there is a shaft 25. This shaft 25 may be supported in bearing blocks 26 secured to the under face of the lower flange 27 of the side bars 11 as illustrated in Figure 3. The shaft 25 has at one end, a right angular extension 28 which lies in the path of a crank extension 29 of a shaft 30 which is provided with an operating knob or handle 31 by which it may be rotated in its bearing 32 which in turn is carried by a corner member 10 of the rack or tree. Upon the right angular extension 28 there is mounted a weight 33 which tends normally to rock the shaft 25 in the counter-clockwise direction as indicated by the arrow C in Figure 1.

Mounted upon the shaft 25 in properly spaced relation to each other, there is a plurality of hub members 36, each of which is rigidly secured to the shaft. Each of these hub members 36 carries two upstanding spaced fingers 37 which straddle the bars 20 of the supporting bars A, it being understood that there will be one of these hub members and its associated fingers

for each of the supporting bars A. The bars 20 are each provided with a cross pin 38 which is adapted for engagement by the upstanding fingers 37 of its respective hub member 36 and these pins together with the fingers 37 provide the means by which the bars 20 of a plurality of supporting bars A may be simultaneously reciprocated to their elevated position with respect to the side members of their respective bars.

The products such as sausages, bolognas or the like are looped upon the supporting bars A in the usual manner before they are positioned in the rack or tree. After the supporting bars have been loaded, they are placed in the rack or tree with one end of the side members 16 thereof occupying positions in the notches 14 heretofore mentioned in the side bars 11 at one side of the rack or tree. The opposite end of each supporting bar is so positioned that its corresponding end of the bar 20 will lie between the two upstanding fingers 37 of one of the hub members 36.

It will be understood that when the supporting bars A are loaded, their bars 20 will occupy a position in which their upper edges are in the same plane or substantially flush with the upper edges 16 of the side members of their respective supporting bars, in which position the bars 20 are illustrated in broken lines in Figure 4.

After the rack or tree has been loaded, it is moved into the smoking chamber or oven and the product carried thereby is subjected to the smoking operation. After the smoking operation has progressed, the rack or tree is removed and the shafts 25 are rotated by grasping their operating knob or handle and turning the same in a clockwise direction. Operations of the shafts 25 in the clockwise direction reciprocates the bars 20 of the supporting bars A to the right as for example in Figure 4, and by reason of the angularly disposed slots 22, the bars will be moved to the elevated position in which one bar is shown in Figure 4. When the bars 20 are in their elevated position, the upstanding fingers 37 of the hub member 36 pass slightly beyond the vertical, which serves to retain the bars in their elevated position until such time as the shaft 25 is rotated in the counter-clockwise direction.

As the shaft is rotated in the counter-clockwise direction, the crank extension 29 thereof moves in a counter-clockwise direction as indicated by the arrow D in Figure 1 permitting the right angular extension 28 of the shaft 25 to move in a counter-clockwise direction as indicated by the arrow C in Figure 1 under the influence of the weight 33 carried by said right angular extension 28. Movement of the shaft 25 in the counter-clockwise direction moves the fingers 37 in a counter-clockwise direction as indicated by the arrow E in Figure 4 and permits the bars 20 of the supporting bars A to move by gravity or under the influence of the weight of the product carried thereby to a position in which their upper edges are substantially flush with the upper edges of the side members 16 of their respective bars.

From the foregoing it will be apparent that the present invention provides a new and improved bar for supporting sausages, bolognas or the like during the smoking process, and that, by reason of its construction, it permits of varying the point of contact of the product being processed with respect to the supporting bar, since when

the bars 20 of the supporting bars are elevated the product being processed is likewise elevated and its point of contact with the side members 16 is different than is the case when the bars 20 are in their lowered position.

In the accompanying drawing the invention has been described in its preferred form, but it is to be understood that it may be practiced in such other forms as rightfully fall within the scope of the appended claims.

Having thus described my invention, what I claim as new is:

1. A device for smoking sausages in combination, a supporting rack or frame and a plurality of sausage supporting bars removably carried thereby, each of said sausage supporting bars comprising a pair of spaced side members, means for securing said side members rigidly together in spaced relation, and an intermediate member slidably mounted between the spaced side members, means carried by the supporting rack or frame for moving simultaneously the sliding member of each of said sausage supporting bars, and means for elevating the intermediate members of said sausage supporting bars to a plane above that of the side members thereof, as sliding movement is imparted in one direction to the sliding members of the bars.

2. A device of the character described comprising in combination, a supporting frame, a plurality of supporting bars carried by said frame, each of said supporting bars comprising two members rigidly secured together in spaced relation, an elevating bar slidably mounted between the members of each of the supporting bars, angularly disposed slotted legs depending from each of said elevating bars, cross pins bridging the spaces between the members of the supporting bars and passing through the slots of the depending legs of the elevating bars whereby the elevating bars will move to and from position between the two members of each of the supporting bars upon longitudinal reciprocating movement of the elevating bars, and means for simultaneously reciprocating said elevating bars.

3. A device of the character described comprising in combination, a supporting frame, a plurality of supporting bars carried by said frame, each of said supporting bars comprising two members rigidly secured together in spaced relation, an elevating bar slidably mounted between the members of each of the supporting bars, angularly disposed slotted legs depending from each of said elevating bars, cross pins bridging the spaces between the members of the supporting bars and passing through the slots of the depending legs of the elevating bars whereby the elevating bars will move to and from position between the two members of the supporting bars upon longitudinal reciprocating movement of the elevating bars, and means for simultaneously reciprocating said elevating bars, said means including a rocking shaft mounted in the supporting frame at a point beneath the supporting bars and at right angles thereto, means carried by said shaft for operative engagement with each of said elevating bars to reciprocate the same between the two members of each of the supporting bars, and means carried by the supporting frame for rocking said shaft.

WILLIAM BOGNER.
